UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

MOTOR DRIVE FOR PRINTING PRESSES

Application filed January 16, 1926, Serial No. 81,761. Renewed October 26, 1929.

This invention relates to the driving of a printing press. The principal objects thereof are to place the motor in such a position that it is entirely out of the way of the operator and can be attended to more easily than under present conditions and is readily accessible for the various adjustments, the application of lubricants and the control of the running of the press.

10 Reference is to be had to the accompanying drawings in which

Fig. 1 is a side view of a printing press, or a unit thereof, showing a preferred embodiment of this invention;

15 Fig. 2 is an end view of the same;

Fig. 3 is a plan thereof; and

Fig. 4 is a sectional view on the line 4-4 of Fig. 2.

Printing presses are frequently run by electric motors and it is customary to place the motor either at the floor level of the press or in a pit built below the floor level. In one case it is necessary to provide the pit at considerable expense and in the other case to provide room on the floor of the press room which, as time goes on, is more and more desirable. There is little space available. In both cases also the location of the motor involves difficulty in getting at it and keeping it in condition and also attending to some parts of the press. It is for avoiding these difficulties that this invention is made.

I have shown the invention as applied to a press of the usual type involving a pair of plate cylinders 10, a pair of impression cylinders 11 and means for guiding the web through the couples from the web roll 12 to a guide roll 13 from which the web is led from the press. The usual inking mechanisms 14 are shown.

Ordinarily this press would be run from a motor below where it would either occupy valuable floor space or necessitate a pit. Instead of either I provide the frame 15 with several uprights 16 on which is located a top 17 made strong and rigid and on this I provide an adjustable plate or rails 18 which constitutes the base for the usual operating motor 19.

50 On the shaft of the motor is a sprocket 21

which through a chain 22a transmits power to a sprocket 22. This latter sprocket is loosely mounted through a sleeve 23 on the end or stud 24 of one of the cylinders. Also loosely rotating on the sleeve 23 is a gear or pinion 25 having a hub 26 to which is keyed the sprocket wheel 22 so that they are free to rotate together independently of the cylinder on the end of which they are located. This gear 25 meshes with a gear 27, which is fixed to the end of an adjacent cylinder 11 and drives it positively from the motor. The several impression and plate cylinders are connected up to each other by gears 28 so that power is transmitted from one to another. In this way all the cylinders are positively driven from the motor. The result is a compact and even drive for the printing press. It reduces the cost of building the foundation for the motor by eliminating the necessity of a pit or reduces the space which the press occupies on the floor. At the same time it provides a rigid support for the motor and locates the motor at about its usual distance from the cylinders which it drives.

Although I have illustrated and described only a single form of the invention I am aware of the fact that modifications can be made therein by any person skilled in the art and it can be applied to many types of presses without departing from the scope of the invention as expressed in the claims.

Therefore, I do not wish to be limited to all the details of construction herein shown and described, but what I do claim is:—

1. In a printing press, the combination of a frame, printing couples supported thereby, said frame extending above the level of the printing couples, an electric motor located on the extension of the frame at a point above the level of the printing couples, and having its shaft parallel with the axles of the printing couples, a sprocket wheel rotated by the motor shaft, a chain connected with said sprocket wheel and means for driving one member of the printing couples directly by said chain.

2. In a printing press, the combination with a support located above and to one side of the printing couples, of a motor carried

by said support, a driving chain operated by the motor, one member of the printing couples having a stud thereon, a sleeve on the stud, a gear loosely mounted to rotate on the sleeve, a gear fixed to said gear in a position to be driven by said chain, and a gear on the member of another printing couple meshing with the first-named gear to be driven thereby.

- 10 3. In a printing press, the combination with a motor, and a driving chain operated by the motor, of printing couples, one member of which has a stud thereon, a sleeve on the stud, a gear loosely mounted to rotate on the sleeve, a gear fixed to said gear in a position to be driven by said chain, and a gear on the member of another printing couple meshing with the first-named gear to be driven thereby.
- 15 4. In a printing press, the combination of a printing couple, one member of which has a stud thereon, a sleeve on the stud, a gear loosely mounted to rotate on the sleeve, a driving wheel fixed to said gear, a motor connected with the drive wheel for operating it, another printing couple, and a gear on one member of the other printing couple meshing with the first-named gear to be driven thereby.
- 20 5. In a printing press, the combination with the printing couples and inking mechanism therefor, a frame for supporting the couples, said frame extending above the level of the printing couples, and a support thereon at its top and adjustable thereon, of a motor mounted in said support above and to one side of the printing couples, and a chain extending direct from said motor to one member of a printing couple for operating all the members of the printing couples.
- 25 40 In testimony whereof I have hereunto affixed my signature.

HENRY A. WISE WOOD.
